B. M. SCHAUMAN

WASHBOILER COVER AND DRAINAGE BOARD

Original Filed March 22, 1921

Fig. 1.

Fig. 2.

UNITED STATES PATENT OFFICE.

BROR MAX SCHAUMAN, OF ATLANTIC HIGHLANDS, NEW JERSEY, ASSIGNOR TO AN ASSOCIATION COMPRISING GRANDIN V. JOHNSON, OTTO GAUTSCHY, AND HARRY W. JOHNSON, ALL OF HIGHLANDS, NEW JERSEY, WILLIAM KOCH, OF LONG BRANCH, NEW JERSEY, AND BROR MAX SCHAUMAN, OF ATLANTIC HIGHLANDS, NEW JERSEY.

WASHBOILER COVER AND DRAINAGE BOARD.

Application filed March 22, 1921, Serial No. 454,459. Renewed June 8, 1925.

To all whom it may concern:

Be it known that I, BROR MAX SCHAUMAN, a citizen of the United States, residing at Atlantic Highlands, in the county of Mon-
5 mouth and State of New Jersey, have in-
vented certain new and useful Improve-
ments in Washboiler Covers and Drainage
Boards, of which the following is a speci-
fication.

10 This invention relates to covers intended particularly for use with wash boilers, and involves a modification of the usual construction of such covers so that they may subserve the additional function of a drainage
15 board.

A further object is to provide a drainage board cover as mentioned above which is very economical to manufacture, and which is readily applied to the boiler either
20 as a cover or as a drainage board.

Other objects and aims of the invention, more or less broad than those stated above, together with the advantages inherent, will be in part obvious and in part specifically
25 referred to in the course of the following description of the elements, combinations, arrangements of parts, and applications of principles constituting the invention; and the scope of protection contemplated will
30 appear from the claims.

In the accompanying drawing, which is to be taken as part of this specification, and in which I have shown a merely preferred form of embodiment of the invention, Figure 1 is a sectional view showing a wash boiler with the combined cover and drainage board attached, showing the latter in its drainage-board relation; and Figure 2 is a perspective view, with parts broken away,
35 illustrating in detail the method of attaching the cover in its drainage-board position.

Referring to the numerals on the drawing, A indicates the wash boiler, and B is
40 the cover for the same, which may be of the ordinary construction, except in the particulars hereinafter set forth. That is to say, it has a flange B' on its lower face which sets into the wash boiler when the
45 cover is used as such, but for the purposes

of my invention this flange B' is provided with drainage apertures E. The cover has also a fin or projection C on its top face along part of one longitudinal edge, and connected with the handle F there is a piv-
55 oted bail D. When the cover is to be used as a drainage board the position of the parts is as shown in the figures, that is to say, the fin C extends down into the boiler, and the bail D is swung down to the Figure 1 po-
60 sition until the bent portion G thereof comes to rest against the connecting bar H of the handle, while the outer end of the bail D comes to rest against the outside of the
65 boiler. The cover is thus sustained in prop-
er position so that any wet clothes put into it will drain, the water passing through the
70 apertures E directly into the boiler. The flange B' of the cover prevents the clothes from sliding off of the drainage board, and therefore has a double function.

It will be understood that the bail D will have to be shaped with reference to the size of the cover and of the boiler so that when the cover is used as the drainage board
75 it will be sustained in the best angular position for that purpose.

Inasmuch as many changes could be made in the above construction, and many apparently widely different embodiments of my
80 invention could be made without departing from the scope thereof, it is intended that all matter contained in the above description or shown in the accompanying drawings shall be interpreted as illustrative and
85 not in a limiting sense.

It is also to be understood that the language used in the following claims is intended to cover all the generic and specific features of the invention herein described
90 and all statements of the scope of the invention which, as a matter of language, might be said to fall therebetween.

I claim:

1. In combination with a wash boiler, a
95 cover for the same having a flange on its lower or inner face and an outwardly extending projection on its outer face parallel to one edge thereof, a brace pivoted on the outside of the cover having its free end
100

1esting against the boiler, and means for limiting the pivotal movement of the brace.

2. In combination with a wash boiler, a cover for the same having a flange on its lower or inner face and an outwardly extending web on its outer face opposite said flange and in alignment with the flange and parallel to one edge of the cover, a bail pivoted on the outside of the cover, and means for limiting the pivotal movement of the bail, said flange of the cover being provided with drainage apertures.

3. In combination with a wash boiler, a

cover for the same having a flange on its inner face and a web projecting from 15 the outer face of the cover and adapted to rest against the inner edge of the boiler, a handle on the outside of the cover and a brace pivoted to and having limited movement on the handle and having its free end 20 resting against the outside of the boiler and cooperative with the web to support the cover on the edge of the boiler.

In testimony whereof I affix my signature.

BROR MAX SCHAUMAN.
